UNITED STATES PATENT OFFICE.

BROR JOHNSON, OF GLASSPORT, PENNSYLVANIA, ASSIGNOR TO UNITED STATES GLASS COMPANY, OF PITTSBURGH, PENNSYLVANIA, A CORPORATION OF PENNSYLVANIA.

DESIGN FOR A GLASS VASE OR SIMILAR ARTICLE.

58,759.

Specification for Design.

Patented Aug. 30, 1921.

Application filed October 13, 1919. Serial No. 330,500. Term of patent 7 years.

To all whom it may concern:

Be it known that I, BROR JOHNSON, a subject of the King of Sweden, and residing at Glassport, in the county of Allegheny and State of Pennsylvania, have invented a certain new, original, and ornamental Design for a Glass Vase or Similar Article, of which the following is a specification, reference being had to the accompanying drawings, forming a part thereof, wherein the single view represents a view in elevation of a glass vase.

The design is shown applied to a vase of conventional form, the shape or outline of which is not claimed.

I claim:

The ornamental design for a glass vase or similar article as shown.

BROR JOHNSON.
